MEANS FOR ATTACHING HEELS TO SHOE BOTTOMS

Filed Oct. 26, 1922

Inventor

Frank Riccioli,
By William W. Deane
his Attorney

UNITED STATES PATENT OFFICE.

FRANK RICCIOLI, OF WASHINGTON, DISTRICT OF COLUMBIA.

MEANS FOR ATTACHING HEELS TO SHOE BOTTOMS.

Application filed October 26, 1922. Serial No. 597,002.

To all whom it may concern:

Be it known that I, FRANK RICCIOLI, a subject of the King of Italy, residing at Washington, District of Columbia, have invented certain new and useful Improvements in Means for Attaching Heels to Shoe Bottoms, of which the following is a specification.

The present application is in part of a continuation of my copending application S. N. 595,822, filed October 20, 1922.

This invention relates to improvements in the method and means of attaching heels to shoe bottoms, and more particularly to the attachment of French heels and the like.

In ladies' foot wear having high heels, the heel on account of its height frequently breaks intermediate its ends, and often the heel in its entirety becomes detached from the shoe. It is the primary object of the present invention to provide means for reinforcing the heel and securing the latter to the shoe.

A further object of the invention is to provide a heel reinforcing and attaching device of simple and inexpensive construction which may be utilized in readily and expeditiously securing a heel to a shoe.

Another object is to furnish a high heel attaching means which will firmly secure the heel in position and reinforce the same without leaving projecting parts liable to irritate the wearer's foot.

With the foregoing objects outlined and with other objects in view which will appear as the description proceeds, the invention consists in the novel features and steps hereinafter described in detail, illustrated in the accompanying drawing and more particularly pointed out in the appended claim.

Referring to the drawing:

Figure 1 is a vertical longitudinal sectional view of the rear portion of a shoe and heel with my improvements.

Figure 2 is a perspective view of the same partly broken away and showing certain of the parts in disassembled relation, to illustrate the manner in which they are applied to the shoe.

Figure 3 is a perspective and vertical sectional view of the tube forming part of the construction, and a side view of the plug which occupies said tube.

Figure 4 is a detail sectional view illustrating the manner of contacting the heel

with the shoe preliminary to making the hole in the shoe bottom.

In the drawing, 1 designates a heel of any suitable construction and preferably of wood provided with a substantially vertical chamber or passageway 2, in which is arranged a reinforcing tube 3, of any suitable material, but preferably of metal. This tube as best shown in Figure 3, is flanged at its lower end, as shown at 3^a. Arranged in this tube is a filler block 4, formed of any suitable material such as wood and adapted to receive a screw 5, employed in securing the lower layer or lift 6, to the bottom of the heel. Tacks or screws 7 may also be employed to aid in securing the lift 6, in place. The tube 3, is inserted from the bottom of the heel and is preferably covered with glue before it is placed in the aperture 2, so that it will be firmly secured in position even though the diameter of the tube is less than the diameter of the passageway 2.

It will be noted that the upper end of the tube 3, projects beyond the concave surface 8, forming the upper face in the heel, and in attaching the heel to the shoe 9, the projecting upper end of the tube is used to form a mark or impression in the lower surface of the bottom 10. As shown in Figure 4, the heel with the tube inserted therethrough is pressed against the bottom 10, after the outer surface of the heel has been aligned with the outer surface of the shoe upper. After this impression is made, a hole may be bored through the bottom 10, at the point impressed, to receive the upper end of the tube 3. By this procedure the heel may be accurately placed in position and the extension of the tube through the bottom 10, will provide a strong connection between the heel and bottom.

After the upper end of the tube 3 is inserted through the aperture 11, formed in the manner indicated, a reinforcing plate 12, of substantially triangular formation with curved edges is placed over the upper end of the tube and a screw 13, is threaded into the tube 3. The head of this screw is preferably flat and enters a countersunk hole 13^a, in the plate 12. Due to this construction the screw head will not project above the upper surface of the plate 12, and form a rough spot liable to irritate the wearer's foot. The threads of this screw engage internal threads 3^b, in the tube and this causes the plate 12, to press on the bot-

- tom 10, and hold the heel in place. After the screw 13, is placed in position, suitable fastening means such as nails 14, or screws 15, may be passed through the plate 12, bot-
5 tom 10, and into the heel 1, and by this construction it will be apparent that a strong bond is provided between the heel and the shoe bottom, and the heel will not turn about the axis of the tube 3.
- 10 After the parts have been secured in position a filling piece 16, of any suitable material, but preferably of leather, may be placed on the upper surface of the bottom 10. This piece is secured in position by
15 gluing the same to the bottom 10, and it is provided with an aperture 17, of the same shape as the plate 12, in order to permit said plate to project through and have its upper surface substantially flush with the upper
20 surface of the filling piece. Finally a lining piece 18, is placed over the plate 12, and filling piece 16, in order to conceal said parts and provide a smooth surface for the wearer's heel. The piece 18, is preferably glued
25 in place.

From the foregoing it is believed that the

construction, operation and advantages of the invention may be readily understood, and it is apparent that various changes may be made in the details disclosed without departing from the spirit of the invention as expressed in the claim.

What is claimed and desired to be secured by Letters Patent is:

The combination with a shoe bottom having an aperture therein, of a heel having a tubular extension extending therethrough and projecting above its upper surface through the hole in said shoe bottom, a plate arranged on the upper surface of said shoe bottom, a screw passing through said plate and engaging the inner surface of the tube, fastening means passing through said plate, shoe bottom and into said heel and arranged at spaced points from said screw, a filling piece surrounding said plate, and a lining arranged over said plate and filling piece for concealing the plate, screw, fastening means and filling piece and providing a smooth upper surface.

In testimony whereof I affix my signature.

FRANK RICCIOLI.
